CLAIM

The ornamental design for a balancing arm for a medical lamp, as shown and described.

DESCRIPTION

FIG. 1 is a front elevational view of a balancing arm for a medical lamp showing our new design, the rear elevational view being a mirror image;

FIG. 2 is a left side elevational view thereof;

FIG. 3 is a top plan view thereof;

FIG. 4 is a bottom plan view thereof;

FIG. 5 is a right side elevational view thereof;

FIG. 6 is a perspective view thereof; and,

FIG. 7 is a side elevational view of the balancing arm with a lamp and support arm shown in broken lines for illustrative purposes only.

FIG. 2

FIG. 1

FIG. 5

FIG. 3

FIG. 4
